FOLDABLE EYEGLASS FRAME

Jack Amster, 1846 Redwood Terrace NW,
Washington, D.C. 20012

Filed Jan. 10, 1967, Ser. No. 5,373

Term of patent 14 years

(Cl. D57—1)

FIG. 1.

FIG. 2.

FIG. 3.

FIG. 4.

FIG. 5.

FIG. 1 is a top plan view of a foldable eyeglass frame embodying my new design;

FIG. 2 is a front view thereof;

FIG. 3 is a side view taken from the left of FIG. 2;

FIG. 4 is a side view taken from the right of FIG. 2; and

FIG. 5 is a top plan view thereof, showing the frame in folded position.

The dominant features of my design reside in the portions shown in full lines.

I claim:

The ornamental design for a foldable eyeglass frame, as shown and described.
